SHOWER STALL

Bruno Verlet, Mourenx, France, assignor to Consortium
Pyrenees Plastiques, Mourenx, France

Filed Sept. 6, 1973, Ser. No. 394,621

Term of patent 14 years

Int. Cl. D23—02

U.S. Cl. D23—57

FIG.1

FIG.2

FIG. 3

FIG. 4

FIG.5

FIG. 1 is a front elevational view of a shower stall showing my new design;

FIG. 2 is a right side plan view thereof;

FIG. 3 is a top plan view thereof;

FIG. 4 is a bottom elevational view thereof; and

FIG. 5 is a perspective view thereof.

I claim:

The ornamental design for a shower stall, as shown.
